(57) **CLAIM**

The ornamental design for the vehicle guard, as shown and described.

DESCRIPTION

FIG. 1 is a front perspective view of a vehicle guard, showing my new design;

FIG. 2 is a front elevational view thereof;

FIG. 3 is a rear elevational view thereof;

FIG. 4 is a left side view of the vehicle guard, the other side being a mirror image thereof; and,

FIG. 5 is a top plan view thereof.

The broken lines shown in FIG. 1 are for illustrative purposes only and form no part of the claimed design.
